(57) **CLAIM**

The ornamental design for an edible pet chew, as shown and described.

DESCRIPTION

FIG. 1 is a front perspective view of the edible pet chew with the claimed design shown in solid lines;

FIG. 2 is a front elevational view of the edible pet chew of FIG. 1;

The rear elevational view of that portion of the claimed design of the edible pet chew is symmetrical to the view shown in FIG. 2; and,

FIG. 3 is a top plan view of the edible pet chew of FIG. 1.

The bottom plan view of the edible pet chew is symmetrical to the view shown in FIG. 3.

The cut lines and the broken line showing of portions of the pet chew form no part of the claimed design.
